GUARD FOR A TOILET PAPER FIXTURE

Samuel L. Gerson, Wilmington, Del.

Application October 17, 1951, Serial No. 16,968

Term of patent 7 years

(Cl. D4—3)

To all whom it may concern:

Be it known that I, Samuel L. Gerson, a citizen of the United States, residing in Wilmington, New Castle County, Delaware, have invented a new, original, and ornamental Design for a Guard for a Toilet Paper Fixture, of which the following is a specification, reference being had to the accompanying drawing, forming a part thereof, in which:

Fig. 1 is a front perspective view of a guard for a toilet paper fixture, showing my new design;

Fig. 2 is a rear perspective view of the guard shown on a reduced scale;

Fig. 3 is a top plan view of the guard; and

Fig. 4 is a front elevational view of the guard.

I claim:

The ornamental design for a guard for a toilet paper fixture, substantially as shown.

SAMUEL L. GERSON.
